BY
his ATTORNEY'S

UNITED STATES PATENT OFFICE.

JOHN B. GRUELLE, OF NEW YORK, N. Y.

DESIGN FOR A TOY DUCK.

47,787.

Specification for Design.

Patented Sept. 7, 1915.

Application filed May 28, 1915. Serial No. 31,071. Term of patent 14 years.

To all whom it may concern:

Be it known that I, JOHN B. GRUELLE, a citizen of the United States, residing at New York, in the county of New York and State of New York, have invented a new, original, and ornamental Design for a Toy Duck, of which the following is a specification, reference being had to the accompanying drawings, forming part thereof.

Figures 1 and 2 are front and side elevations respectively of a toy duck, showing my new design.

I claim:

The ornamental design for a toy duck, as shown.

JOHN B. GRUELLE.
